SAFETY PIN OR THE LIKE

Eugene S. Drake, 2836 Kansas Ave.,
Southgate, Calif. 90280

Filed Oct. 14, 1966, Ser. No. 4,284

Term of patent 14 years

(Cl. D2—413)

FIGURE 1 is a perspective view of a safety pin or the like showing my new design in open condition;

FIGURE 2 is a front elevational view thereof in closed condition;

FIGURE 3 is a side elevational view thereof;

FIGURE 4 is a bottom plan view thereof;

FIGURE 5 is a side elevational view thereof in open condition;

FIGURE 6 is a sectional view taken on line 6—6 of FIGURE 3;

FIGURE 7 is a perspective view thereof as seen from the bottom; and

FIGURE 8 is a fragmentary perspective view of the safety pin or the like of FIGURE 1 wherein the finger engaging button is devoid of protrusions on the exterior and concave on the lower surface thereof.

I claim:

The ornamental design for a safety pin or the like, substantially as shown and described.
